UNITED STATES PATENT OFFICE.

WALTER A. O'BANNON, OF TULSA, OKLAHOMA, ASSIGNOR TO WALTER A. O'BANNON COMPANY, OF TULSA, OKLAHOMA.

SAFETY HOOK.

Original No. 1,582,345, dated April 27, 1926, Serial No. 75,051, filed December 12, 1925. Application for reissue filed March 30, 1929. Serial No. 351,334.

The present invention relates to the art of appliances used in conjunction with well works, and is conventionally known as a safety hook.

5 The common form of such a device consists of an open hook generally of the swivel type but owing to the frequency with which these hooks become disengaged from the object which is being handled thereby, it is customary to provide them with guard latches which extend across the throat of the hook opening.

10 It is to this form of device that the present invention relates, its object being to provide such an appliance with manually operable means whereby the opening of the hook or latch will take place as an incident to the pressure of the operator's hand in the hook-off movement.

15 It is of prime importance in these devices that projecting parts be eliminated as far as possible to prevent the accidental unlocking of the hook incident to its engagement with the rigging, and therefore it has been 20 my aim to dispose the operating means for the hook latch in a manner which will preclude catching any object with which it might come in contact.

25 It is further an important characteristic of my safety hook that in form or shape it is not unduly large at that portion which is grasped by the operator's hand, thereby 30 greatly facilitating the operations of hooking and unhooking, this phase of the apparatus influencing the arrangement and structure of the parts forming the latch mechanism.

35 Other and further objects and advantages of the invention will be hereinafter set forth and the novel features thereof defined by the 40 appended claims.

In the drawing:

45 Fig. 1 is a side elevation of a safety hook constructed in accordance with my invention, partly broken away to show more clearly the details of construction and arrangement of the latch mechanism;

50 Fig. 2 is a front elevation with the swivel and bearing omitted;

55 Fig. 3 is a horizontal sectional view on the line 3—3 of Fig. 1;

60 Fig. 4 is a horizontal sectional view on the line 4—4 of Fig. 1;

Fig. 5 is a detail view of the lower end of a modified form of latch lever;

55 Fig. 6 is a fragmentary view showing the interlocking slot in the latch with which the extremity of the latch lever coacts;

60 Fig. 7 is a side elevation of a modified form of safety hook, the body of the hook being broken away to disclose the latch and operating lever mounted thereon;

65 Fig. 8 is a front elevation of the hook device shown in Fig. 7; and

70 Fig. 9 is a detail view of the locking detent and operating lever therefor, taken from the side opposite that shown in Fig. 7.

75 Like character of reference designate corresponding parts throughout the several figures of the drawing.

70 Referring to the drawing, 1 designates the body portion of the hook which at its top is formed with the threaded stud 2 to receive the swivel bail 3 secured thereon by the nut 4. A roller bearing 5 is employed in conjunction with this swivel mounting.

75 The latch mechanism which forms the special feature of this invention is mounted in the shank portion of the hook above the opening of the same and for this purpose the 80 material of the hook body is channeled out as indicated at 6 to receive the several parts. Within the lower enlarged portion of this channel formed in the offset 7 of the body is pivotally mounted the latch member or 85 guard 8, which depends vertically from the pivot 9 across the entrance to the hook and in abutting relation to the wall 10 which prevents outward movement of the latch, thereby resisting any inclination of the load to 90 jump out.

90 This latch is designed to be retired into its receiving recess or seat, the enlarged portion of the channel 6 above referred to, by the lever 11 which is pivotally connected at 95 12 adjacent the top of the hook, the lower end having an interlocking shiftable connection with the latch 8. The particular form of this connection may differ. In Fig. 1 the latch lever 11 is provided with a lateral extension 12' which extends into a slot 8' in the latch member. The connection is a 100 slideable one because of the swinging movement which it is necessary to impart to the latch member 8. The construction may be modified as shown in Figs. 5 and 6 by forming 105

an undercut groove 8" in the rear face of the latch member and within this the opposite extensions 11" of the latch lever are free to ride in the operation of the latch.

5 To maintain the latch normally in operative or closed position shown in full lines in Fig. 1, a spring 13 is mounted in rear of the lever 11 which presses the latch against the wall 10.

10 It will be clear that in the operation of this hook, the operator needs only to move it into engagement with the object to be handled, the latch 8 yielding readily to pressure thereagainst and allowing the object to pass into the hook opening. When the unhooking operation is to be effected the operator's hand is about the neck or shank portion of the hook and in drawing the same toward him to cause the disengagement he exerts pressure against 15 the front of the hook and the shank portion of the latch lever 11 which projects slightly from the surface of the hook body. This causes the latch member 8 to completely retire into its seat in the offset 7, leaving the hook opening completely free and unobstructed. It will be apparent that this unlatching movement is automatically produced, so to speak, in the natural unhooking of the safety device 20 from the object which it carries.

25 Referring to Figs. 7, 8 and 9 which show a modified form of my invention, the detent or latch 8^a is provided with the curved slot 8^b of slightly greater width at the top 8^e than the bottom, and provided on one wall with a 30 raised portion in the form of a lug or cam 8^d. The lateral extension 12' of the release lever 11 is slidably interlocked in the slot 8^b. The lever 11 is also provided with a shoulder 11^a adapted to engage the shoulder 8^c of the 35 detent 8^a and retain or lock the detent against inward movement.

40 The widened portion 8^e of the slot is provided in order that the actuating lever 11 may be permitted to move inwardly sufficiently to 45 disengage the shoulder 11^a on the lever 11 and the shoulder 8^c on the detent and unlock said detent. This initial movement may be termed the unlocking movement and is shown in the intermediate dotted line position of Fig. 9. 50 Upon further inward movement of the lever 11, in the direction of the small arrow in Fig. 9, the extension 12' will engage the side of the slot 8^b moving the detent 8^a inwardly from across the throat 1^a of the hook 1. This movement after the initial unlocking movement is 55 the same as previously described in the descriptions of my preferred form. After the lever 11 has been pressed in, causing the detent to be withdrawn and the operator releases the said lever, the spring 13 moves the 60 same outwardly, causing the detent 8^a to be moved across the opening 1^a of the hook. It is essential that the detent be moved to normal closed position before the lever 11 moves 65 to final locking position.

To accomplish this function the cam or projection 8^d on the wall of the slot 8^b is so positioned that the lever 11 will move or cam the detent 8^a completely to closed position before the lateral extension 12' can pass into the wider end 8^e of the slot 8^b and permit the shoulders 8^c and 11^a to engage, locking the detent positively against accidental movement.

70 It will be comprehended readily by the construction as disclosed in this modification that while the operator may readily and easily open the hook with one hand, upon release of the latch lever 11 the detent 8 will not only be returned to normal position closing the 75 mouth 1^a of the hook 1, but will positively lock the detent 8^a in this position, thereby preventing the hook from accidentally catching on any object, while at the same time obviating 80 any possibility of accidentally disengaging 85 the load.

In view of the use of a relatively long latch lever 11 a considerable degree of swinging movement is capable of being imparted to the latch member 8 by a very slight movement 90 of said latch lever and hence it is necessary for this lever to project from the body of the hook very slightly. The strength of the hook is not materially weakened by the arrangement of this simple form of latch mechanism 95 in the same, this being provided against in many of the safety hooks by materially enlarging the body of the hook to accommodate the latch mechanisms. Such enlargement of the hook body makes it difficult for the operator 100 to grasp the hook comfortably and frequently this leads to accident because these bodies are relatively heavy under ordinary conditions.

105 It will be apparent that the latch mechanism which forms the subject matter of this invention is of a very simple character and may be cheaply manufactured, and I desire it to be understood that modifications in the form and arrangement thereof may be made 110 without departing from the spirit of the invention and within the scope of the claims hereto appended. Such modification of the locking arrangement may consist of the omission of the shoulders 8^c and 11^a, under which 115 conditions the parts would still remain in a locking position by virtue of the cooperation of the projection 12' with the cam 8^d, as shown particularly in Figs. 7 and 9.

120 Having thus described my invention, what I claim as new and desire to secure by Letters Patent is:

1. A safety device of the class described comprising a hook body, a latch member suspended across the entrance of the hook, and actuating means pivotally mounted at one end above the latch in the shank portion of the hook to swing in the direction of hooking off for displacing the latch from across the hook entrance and operatively engaging the latch 125 130

at its other end, said actuating means being operable in the direction of and as an incident to the application of pressure to the hook for hooking off movement of the same.

- 5 2. A safety device of the class described comprising a hook body, a latch member extending across the entrance of the hook body, and separate actuating means connected at one end to the latch member and pivotally mounted at the other end in the hook body above the latch connection aforesaid to swing in a direction rearwardly of the hook incident to the application of pressure to the hook for hooking off movement of the same.
- 10 3. A safety device of the class described comprising a hook body, a latch member extending across the entrance of the hook body, and an actuating member pivotally mounted at one end in the hook body and having a connection at its other end to the latch member capable of locking the latch against movement from pressure against the latch when in closed position, said latch member being free to open upon application of pressure to the actuating member.
- 15 4. A safety device of the class described comprising a hook body, a latch member mounted above the opening of the hook so as to normally depend across said opening, means limiting the movement of the latch member in one direction, and a pivoted lever extending along the shank of the hook where grasped by the operator normally locking the latch member and having a shiftable connection with said latch member to release the same upon initial movement of the lever, said lever being operable upon further movement to open the latch.
- 20 5. A safety device of the class described comprising a hook body having a channel extending longitudinally of the same and terminating in an enlarged recess, a latch member pivotally mounted on the hook body to extend across the opening of the hook, lever means having shiftable connection with the latch member at one end and pivotally mounted on the hook member in the channel aforesaid, said latch lever being operable to shift the latch member completely into the enlarged recess aforesaid.
- 25 6. A safety device of the class described comprising a hook body, a latch member pivotally mounted above the opening of the hook so as to normally extend across said opening, an actuating member mounted on the body and having connection with said latch member for swinging the same from the position aforesaid into inoperative position, and projecting means on the body extending over the hook and constituting a guard for the hook and latch.
- 30 7. A safety device of the class described, comprising a hook body, a latch member extending across the entrance of the hook, and pivotally mounted actuating means for operating the latch member, said actuating means constituting a locking means for the latch member.
- 35 8. A safety hook comprising a hook body, a detent adapted to close the entrance to the hook body, locking means for holding the detent across the hook opening, and pivoted actuating means for releasing the locking means and moving the detent out of the opening.
- 40 9. A safety hook comprising a hook body, a latch member pivotally mounted across the opening of the hook so as to normally close said opening, an actuating member pivoted at one end to the hook body and having interlocking engagement with the latch member for swinging the latch member, and locking means for the latch member operated incident to movement of the actuating member.
- 45 10. A safety device of the class described comprising a hook body, a latch member pivotally mounted above the opening of the hook so as to normally depend across said opening, means limiting the movement of the latch member in one direction, a lever extending along the shank of the hook where grasped by the operator having shiftable connection with the latch at one end and pivotal connection with the hook at the other end, said lever being operable to swing the latch from said normal position into the hook body, and interlocking means between the latch member and the lever for normally locking the latch member from movement, said means being moved into inoperative position incident to the movement of the lever.
- 50 11. A safety device of the class described comprising a hook body having a channel extending longitudinally of the same and terminating in an enlarged recess, a latch member pivotally mounted on the hook body to extend across the opening of the hook, lever means having shiftable connection with the latch member at one end and pivotally mounted on the hook member in the channel aforesaid, said latch lever being operable to shift the latch member completely into the enlarged recess aforesaid, and locking means for the latch member operable incident to initial latch shifting movement of the lever to unlock said latch member.

In testimony whereof I affix my signature.
WALTER A. O'BANNON.

CERTIFICATE OF CORRECTION.

Reissue Patent No. 17,390.

Granted July 30, 1929, to

It is hereby certified that the name of the patentee in the above numbered patent is erroneously written and printed as "Walter A. O'Bannon", whereas said name should have been written and printed as "Walter O'Bannon"; and that the said Letters Patent should be read with this correction therein that the same may conform to the record of the case in the Patent Office.

Signed and sealed this 20th day of August, A. D. 1929.

(Seal)

M. J. Moore,
Acting Commissioner of Patents.
